DISTILLATE PETROLEUM PRODUCT AND
METHOD OF TREATING SAME

James B. Rather and Leslie C. Beard, Jr., Brook-
lyn, and Orland M. Reiff, Jackson Heights,
N. Y., assignors to Socony-Vacuum Oil Com-
pany, Incorporated, New York, N. Y., a corpo-
ration of New York

No Drawing. Original application November 26,
1926, Serial No. 151,005. Divided and this ap-
plication May 23, 1933, Serial No. 672,514

5 Claims. (Cl. 44—9)

This application is a division of our copending
application Serial No. 151,005, filed November 26,
1926.

This invention relates to distillate petroleum
products and to method of treating same to pre-
vent spontaneous discoloration and formation of
odor therein.

It is well recognized that the distributors and
consumers of kerosene and gasoline insist that
10 these products be clear and free from discolora-
tion and odor as an entirely distinct and separate
matter from the actual capabilities and usefulness
of the products for the ordinary uses for which
they are intended. It is also well recognized that
15 kerosene and gasoline spontaneously become un-
clear, discolored and odorous gradually upon con-
tinued exposure to air, thus after a while becom-
ing objectionable to the trade.

The principal object of this invention is to pro-
20 vide a distillate petroleum product, notably kero-
sene and gasoline, which will remain clear and
free from discoloration and odor without im-
pairment or lowering of its effectiveness and ca-
pabilities for use; and to provide a simple and in-
25 inexpensive method of producing a distillate pe-
troleum product having the characteristics and
qualities referred to.

Other objects of this invention will be in part
obvious and in part pointed out hereinafter.

In accordance with this invention, the improved
30 product consists of a petroleum distillate, notably
kerosene and gasoline, containing a negative ox-
idation catalyst. The catalyst may be added in
the still during distillation, or placed in the con-
denser in which the distillate is condensed, or the
35 catalyst may be added to the distillate after re-
moval from the condenser, it being advisable,
however, to add the catalyst before any appreci-
able quantity of atmospheric oxygen has been tak-
en up by the distillate, because such oxygen is
40 apt to cause the formation in the distillate of
substances which are apt to promote the addition
of further oxygen and may tend to offset any
advantage to be gained by the subsequent addi-
45 tion of the negative oxidation catalyst. These
objectionable substances, while frequently color-
less and odorless, are apt to undergo change re-
sulting in the development of objectionable color
and odor.

50 The negative oxidation catalysts or catalysts
should be of such nature that when added to
kerosene or gasoline in sufficient quantities for
the purpose they do not affect the color and odor,
or materially increase the cost of production, since

such effects would raise commercial objections to
the product.

If the distillate requires to be sweetened either
before or after treatment with the catalyst, the
catalyst should be of a nature such that it will
not react with sodium plumbite. 5

The following substances and classes of sub-
stances are mentioned as suitable for the treat-
ment above described:

Aliphatic alcohols; for instance, a butyl alcohol. 10

Aromatic alcohols; for instance, benzyl alcohol.

Aromatic aldehydes; for instance, benzyl al-
dehyde.

Aromatic amines; for instance, alpha naphthyl-
amine. 15

Substituted phenols and poly phenols; for in-
stance, cresol and hydroquinone.

Ureas and urea derivatives; for instance, urea
and thiourea.

Alkaloids; for instance, brucine and nicotine. 20

For the practice of this invention we prefer
to use secondary or tertiary butyl alcohol alone
or in admixture with hydroquinone or brucine.
In the latter case a saturated solution of hydro-
quinone or brucine in secondary or tertiary butyl
alcohol is used, the secondary or tertiary butyl
alcohol serving to facilitate the solution of the
hydroquinone or brucine in the oil. The amounts
of secondary or tertiary butyl alcohol, or of the
saturated solution of hydroquinone or brucine
in secondary or tertiary butyl alcohol, may vary 30
from 1 part in 5 thousand to 1 part in 50
thousand, depending upon the amount of stabili-
zation desired, the character of the distillate,
i. e., its susceptibility to oxidation, and the
storage temperature. 35

Any of the above mentioned substances are
suitable either alone or in combination with
others. It is never required to add more than
0.02% to the kerosene or gasoline, and the
amount may be as small as 1 part negative cata-
lyzer to 500 thousand parts oil. 40

It will be apparent from the above that this
invention is directed primarily to preventing dis-
coloration and formation of odor in the lighter
petroleum distillates, notably those of A. P. I.
gravity higher than 37 degrees, and particularly
kerosene and gasoline. Consumers and distribu-
tors of these products require that they be clear
and free from discoloration and objectionable
odor without considering the question of ser-
viceability for the use intended. 45

Kerosene and gasoline, however, must be main-
tained comparatively inexpensive in order to sat-
isfactorily cope with commercial competition, and 55

therefore any treatment must be such that the cost of production is not increased a prohibitive amount. Applicants' method satisfactorily meets this delicate situation since the amounts of negative catalyst the treatment requires are so small that increase in the cost of manufacture and price to the consumer is negligible. At the same time the treated kerosene and gasoline is capable of being stored and handled without 10 danger of its becoming discolored or odorous.

It is understood that this invention is not intended to be limited to the precise substances mentioned specifically, nor to the exact proportions stated, since applicants have described 15 merely certain possible applications of the invention which are preferred at this time.

We claim:

1. The method of stabilizing the characteristics of a low boiling light colored distillate petroleum 20 product of the class of gasoline or kerosene that normally tends to develop objectionable products of oxidation during storage, which may be evidenced generally by discoloration of the product which comprises adding to the product and sub- 25 stantially completely dissolving therein a small quantity of urea sufficient substantially to retard the formation of said objectionable products of oxidation, but not more than 0.02%.

2. The method of stabilizing the characteristics 30 of a low boiling light colored distillate petroleum product of the class of gasoline or kerosene that normally tends to develop objectionable products of oxidation during storage, which may be evidenced generally by discoloration of the product which comprises adding thereto a small quantity of thiourea sufficient 35 substantially to retard the formation of said objectionable products of oxidation.

3. A low boiling light colored hydrocarbon fuel product of the class of gasoline or kerosene normally tending to develop objectionable oxidation products during storage, which may be evidenced generally by discoloration of the product having added thereto and substantially completely dissolved therein, as an addition agent incorporated into the said product which normally does not contain said agent, a small quantity of a derivative of urea sufficient in amount substantially to 10 retard the formation of said objectionable products of oxidation, but not more than 0.02%.

4. A low boiling light colored hydrocarbon fuel product of the class of gasoline or kerosene normally tending to develop objectionable oxidation 15 products during storage, which may be evidenced generally by discoloration of the product having added thereto and substantially completely dissolved therein, as an addition agent incorporated into the said product which normally does not 20 contain said agent, a small quantity of urea sufficient in amount substantially to retard the formation of said objectionable products of oxidation, but not more than 0.02%.

5. A low boiling light colored hydrocarbon fuel 25 product of the class of gasoline or kerosene normally tending to develop objectionable oxidation products during storage, which may be evidenced generally by discoloration of the product having added thereto, as an addition agent incorporated into the said product which normally does not 30 contain said agent, a small quantity of thiourea sufficient in amount substantially to retard the formation of said objectionable products of oxidation.
